UNITED STATES PATENT OFFICE.

JAMES ELY, OF ROCHESTER, NEW YORK, ASSIGNOR TO TAYLOR INSTRUMENT COMPANIES, OF ROCHESTER, NEW YORK, A CORPORATION OF NEW YORK.

SENSITIVE DIAPHRAGM FOR LIGHT PRESSURE.

Application filed July 22, 1926. Serial No. 124,245.

This invention relates to an improvement in apparatus for measuring and recording pulsating pressures and more in particular to an improvement in apparatus of the type 5 disclosed in the patent to Levin No. 1,532,705.

In instruments for recording small pulsating pressure variations or, more in particular, for translating pulsating pressure 10 actions of the blood upon the constricting cuff mechanism to a recording mechanism, a pressure-responsive element of high sensitivity must be provided.

Of all the pressure-responsive devices 15 available for similar purposes, the resilient diaphragm construction is best adapted for carrying out the particular object. However, only comparatively few materials have been found suitable to satisfy the practical 20 requirements. Of all the materials experimented with, such as for instance admiralty nickel metal, aluminum, steel, brass, bronze, oiled silk, bakelite varnish on thin paper, parchment celluloid gave the best results.

25 However it was found that under some conditions the celluloid diaphragm was subject to variations of sensitiveness and response and in some instances became even inoperative for the purposes of the invention, 30 due to absorption of moisture from the air. While celluloid is not highly hygroscopic, the action of moisture upon the diaphragm may affect its physical and mechanical characteristics depended upon for 35 accurate response to the fluid pressure impulses, to such an extent as to materially impair its utility for the particular purpose.

Various remedies have been tried but have failed to give the desired effect without 40 impeding the mechanical qualities of the diaphragm.

The object of the invention is a means for 45 protecting sensitive diaphragms of the character involved without material impairment of the mechanical properties thereof depended upon for sensitive response to variations of pressure.

I have found that thin sheets of alum-tanned colon leather placed loosely on one or 50 both sides of the diaphragm affords a shield or screen against the action of moisture and at the same time do not materially interfere with the normal intended function of the diaphragm.

55 In the drawing, which forms a part of the

specification, the invention is illustrated as forming part of a diaphragm construction for use in connection with a recording sphygmomanometer such as disclosed in the application of George B. Ireland Serial No. 60 124,220 filed July 22, 1926, the drawing being a central sectional view through the diaphragm.

The diaphragm construction herein shown consists of a rigid housing composed of two 65 complementary halves 1 and 2 having flanges 1^a and 2^a bolted together and holding between them in clamped relation, as is usual, the diaphragm 3. The nipples 4 and 5 are provided for affording detachable pneumatic 70 connections to the opposite sides of the diaphragm 3. The stem 6 projecting from the center of the diaphragm constitutes one of the elements for translating motion of the diaphragm to indicating or recording mechanism which does not form a part of the 75 present invention.

The construction thus far described may be considered as representing ordinary engineering practice and prior art so far as its 80 relation to the invention proper is concerned.

The diaphragm 3 with which the invention is more particularly associated is of celluloid and has a thickness of about .0015". In analogy to the general practice relating to 85 diaphragm constructions, the diaphragm 3 is formed to present a plurality of concentric undulations for increasing the range of movement.

On opposite sides of the diaphragm are 90 disposed sheets 7 and 8 of alum-tanned colon leather the thickness of which is of the order of .0005". The sheets or disks are co-extensive with the diaphragm and are clamped at the periphery between the flanges 1^a and 2^a, 95 preferably together with gaskets 9 and 10 and at the center between washers 11 or the like held together by means of nuts 12 co-operating with the screw-threaded stem 6.

The disks 7 and 8 of colon leather are so 100 dimensioned and disposed that they overlie the diaphragm in a slack condition i. e. so that they can readily follow the movement of the diaphragm without exerting a pressure upon it. It should be noted that the 105 diaphragm is preferably disposed in a vertical direction so that not even the weight of the leather, as negligible as it is, can have a material effect upon the action of the diaphragm.

The colon leather is so thin and so extremely flexible and pliable that under the pneumatic pressure actions transmitted to it or due to varying differences of pressure existing on opposite sides of the diaphragm, the disks 7 and 8 transmit the pressure impulses or yield to pressure impulses without substantially modifying the motion of the diaphragm or in any way superimposing upon the motion of the latter characteristics which are not functions of the diaphragm proper.

While I have made special reference to a celluloid diaphragm and while celluloid is believed to be the most suitable material for diaphragms of the character involved, the invention is in no wise limited thereto.

I claim:

1. In pressure-responsive devices of the diaphragm type, the combination of a diaphragm sensitive to small changes in pnu-

matic pressure and a shield against influences of moisture, said shield comprising a thin sheet of pliable material of the order of alum-tanned colon leather.

2. In a pressure-responsive device of the diaphragm type, the combination of a diaphragm sensitive to small changes in pneumatic pressure and a shield against influences of moisture, said shield comprising a thin sheet of pliable material of the order of alum-tanned colon leather on each side of the diaphragm.

3. In pressure-responsive devices of the diaphragm type, the combination of a celluloid diaphragm having a thickness of about .0015" and a shield against influences of moisture comprising a sheet of alum-tanned colon leather having a thickness of about .0005".

In testimony whereof I affix my signature.
JAMES ELY.
